ATTORNEY.

UNITED STATES PATENT OFFICE.

CHARLES E. MASON, OF SAN FRANCISCO, CALIFORNIA.

MASSAGING DEVICE.

SPECIFICATION forming part of Letters Patent No. 709,103, dated September 16, 1902.

Application filed January 10, 1902. Serial No. 90,628. (No model.)

To all whom it may concern:

Be it known that I, CHARLES E. MASON, a citizen of the United States, residing at San Francisco, in the county of San Francisco and State of California, have invented certain new and useful Improvements in Massaging Devices, of which the following is a specification.

My invention relates to improvements in massaging devices, the object of my invention being to provide a simple and inexpensive device by means of which the skin of the face of the patient can be drawn out or moved from side to side in any direction under a powerful yet gentle application of force without the direct contact of the fingers of the masseur.

A further object of my invention is to provide a device of this character by which the skin can be placed under tension substantially upon immediate contact of the device therewith, so that massaging can be applied to the skin as rapidly as with the fingers and with better effect.

My invention therefore resides in the novel construction, combination, and arrangement of parts for the above ends hereinafter fully specified, and particularly pointed out in the claims.

In the accompanying drawings, Figure 1 is a side view of my improved device. Fig. 2 is a longitudinal section of the same. Fig. 3 is an end view thereof, and Fig. 4 is an enlarged section of an end of the device.

Referring to the drawings, 1 represents a tube or cylinder of soft rubber, corrugated, as shown at 2, to produce accordion folds, thereby enabling said rubber cylinder to be more readily compressed lengthwise. The ends of said cylinder are closed by metallic caps 3, having recessed flanges 4. In said recesses are received the enlarged or thickened terminal edges 5 of the cylinder, said edges being clamped in said recesses by means of rings 6, thereby producing air-tight joints between the caps and cylinder. From one side of the cylinder, at the middle of its length, extends the bell-shaped mouth 7, also of soft rubber and formed integral with said cylinder.

The circular lip 8 of said mouth is stiffened by means of a ring 9, of wire, enveloped in said lip. Between the two end caps 3 is interposed

a compressed spiral spring 10, having a constant tendency to press the end caps apart from each other and to expand the cylinder 55 to its utmost extent.

The device is used in the following manner: The operator presses the two ends of the device as close together as possible by means of his fingers and thumb and applies the device while thus compressed to the face of the patient so that the bell-shaped mouth shall be in close contact with the skin at the point to which it is desired to apply the massage treatment. Upon removing the pressure the 65 coiled spring 10 immediately separates the two ends against atmospheric pressure. A vacuum is thus produced within the device, so that the atmospheric pressure in the body of the patient forces the skin up within the 70 bell-shaped mouth. The stronger the spring 10 the more perfect is the vacuum produced.

An important feature of my invention resides in the interposition of the spring 10 between the ends of the cylinder. This has the 75 result of producing a vacuum and suction on the skin immediately on contact, so that massaging can take place with great rapidity.

A further important feature of my invention is the flexible character of the neck of 80 the bell-shaped mouth. This enables the device to be moved laterally while clinging to the skin, so that a lateral tension in any direction can be imparted to any desired portion of the skin. By this construction I provide a device by means of which the skin can be raised at any desired point and moved from side to side as the device is moved along the surface of the part to be massaged, thus enabling me to massage the face in a very 85 effective and convenient manner.

I claim—

1. A massage device comprising a vacuum-chamber having two end walls and a flexible cylindrical wall joining said end walls, a 95 spring acting between said end walls to separate them, a non-collapsible suction-mouth, a flexible neck connecting said mouth directly with said flexible wall, substantially as described.

2. A massage device comprising a vacuum-chamber having two end walls and a flexible cylindrical wall corrugated lengthwise joining said end walls, a spring acting between

said end walls to separate them, a non-collapsible suction-mouth, and a flexible neck connecting said mouth directly with said flexible wall, substantially as described.

- 5 3. A massage device comprising a vacuum-chamber having two end walls and a flexible cylindrical wall joining said end walls, a spring acting between said end walls to separate them, a non-collapsible suction-mouth, 10 and a short flexible neck connecting said

mouth directly with said flexible wall and made in one piece therewith, substantially as described.

In witness whereof I have hereunto set my hand in the presence of two subscribing witnesses. 15

CHAS. E. MASON.
